(57) **CLAIM**

The ornamental design for an air intake tubing for utility terrain vehicle, as shown and described.

DESCRIPTION

FIG. 1 is a first perspective view of an air intake tubing for utility terrain vehicle showing the new design.

FIG. 2 is a second perspective view of an air intake tubing for utility terrain vehicle showing the new design.

FIG. 3 is a front view of an air intake tubing for utility terrain vehicle showing the new design.

FIG. 4 is a rear view of an air intake tubing for utility terrain vehicle showing the new design.

FIG. 5 is a bottom view of an air intake tubing for utility terrain vehicle showing the new design.

FIG. 6 is a top view of an air intake tubing for utility terrain vehicle showing the new design.

FIG. 7 is a first side view of an air intake tubing for utility terrain vehicle showing the new design; and,

FIG. 8 is a second side view of an air intake tubing for utility terrain vehicle showing the new design.

The broken lines are to show environmental structure only and form no part of the claimed design.

1 Claim, 6 Drawing Sheets
